UNITED STATES PATENT OFFICE.

GEORGE W. BLAIR, OF PITTSBURG, PENNSYLVANIA.

DESIGN FOR A LAMP-SHADE.

SPECIFICATION forming part of Design No. 36,591, dated October 20, 1903.

Application filed March 27, 1902. Serial No. 100,331. Term of patent 3½ years.

To all whom it may concern:

Be it known that I, GEORGE W. BLAIR, of Pittsburgh, Allegheny county, Pennsylvania, have invented a new, original, and ornamental Design for Lamp-Shades, which is shown in the accompanying drawings, in which—

I claim—

The ornamental design for a lamp-shade, as shown.

In testimony whereof I have hereunto set my hand.

GEORGE W. BLAIR.
